UNITED STATES PATENT OFFICE.

WILLIAM E. ELLIOTT, OF GRAND RAPIDS, MICHIGAN, ASSIGNOR TO AMERICAN
BUTTON & FASTENER COMPANY, A CORPORATION OF MAINE.

MACHINE FOR APPLYING FASTENERS.

1,313,941.

Specification of Letters Patent. Patented Aug. 26, 1919.

Application filed October 30, 1916. Serial No. 128,618.

To all whom it may concern:

Be it known that I, WILLIAM E. ELLIOTT, a citizen of the United States of America, residing at Grand Rapids, in the county of Kent and State of Michigan, have invented certain new and useful Improvements in Machines for Applying Fasteners; and I do hereby declare the following to be a full, clear, and exact description of the invention, such as will enable others skilled in the art to which it appertains to make and use the same.

This invention relates to a machine for applying fasteners to a piece of work. While certain features are particularly adapted to button attaching machines of the type illustrated in which an attaching staple is formed from wire threaded through the eye of a button, the invention as a whole is not thus limited.

Button attaching machines commonly are arranged to remove one button from a quantity of buttons, position it and attach it to the work. Most of these machines are provided with a hopper containing a quantity of buttons in an indiscriminate mass and these buttons are then removed and delivered one at a time to a positioning mechanism, usually by way of a raceway adapted to contain several buttons arranged in similar positions. The devices used for lifting the buttons out of the hopper and placing them in the raceway are haphazard in their operation and tend to scar the buttons by constant agitation.

An object of this invention is to provide an improved button attaching machine having means for individually and temporarily supporting a plurality of buttons together with means for removing said buttons from their temporary support and attaching them one at a time to the work.

The stripper mechanism *per se*, for removing the buttons from their temporary support, and certain allied features relating to the feeding of the buttons have not been claimed in this application since they are included in the subject-matter of a divisional application, Serial No. 158,996, filed March 31, 1917, and the stripper mechanism broadly has been claimed in my copending application, Serial No. 87,215, filed March 28, 1916.

With the hopper and raceway arrangements in use, there can be no certainty that

the number of buttons supplied to the raceway will bear any fixed relation to the number of buttons removed for attachment to the work. Accordingly, there is no surety that the raceway will be just full enough 60 and not either overflowing or nearly empty.

It is another object of the invention to provide operating mechanism for a button attaching machine constructed and arranged to actuate the stripper mechanism associated 65 with one end of the raceway and other mechanism, such as button positioning, threading, or attaching means, associated with the other end of the raceway, in conjunction and with a predetermined speed ratio. The 70 illustrated arrangement is intended to insert one button in the raceway for every button removed but it is obvious that other speed ratios may be found desirable.

A type of button is in use which is more 75 fully illustrated and described in Letters Patent of the United States to W. E. Elliott, No. 1,206,755, granted Nov. 28, 1916. This button has a boss or neck upon its base which prevents wear of the buttonhole and 80 assists in the operation of unbuttoning the shoe, and a special raceway, having a shallow groove adjacent to the eye receiving groove, is necessary for handling them. As described and claimed in my copending application, Serial No. 128,617, filed Oct. 30, 1916, this raceway is preferably notched at 85 its end to enable the eye of the button to be fully exposed and to provide button supporting extensions. 90

A feature of this invention relates to the combination of such a raceway with a novel staple former anvil constructed and arranged to coöperate with the button supporting extensions to provide a three point 95 support having certain advantages to be later described.

Another feature of the invention relates to the construction of this novel staple former anvil. 100

Other features of the invention relative to the construction of the raceway, and its combination with other instrumentalities, will be more fully understood from a consideration of the following specification, 105 taken in connection with the accompanying drawings, in which:—

Figure 1 is a side elevation of a mechanism embodying my invention.

Fig. 2 is a plan view of the button strip- 110

ping mechanism and the transfer tube for the buttons.

Fig. 3 is a side elevation of the construction shown in Fig. 2.

5 Fig. 4 is a perspective view of the button stripper mechanism and the receiving end of the transfer tube or raceway, with parts broken away.

Fig. 5 is a vertical longitudinal section 10 through the stripper mechanism.

Fig. 6 is a perspective view of the forward end of the raceway showing the staple former anvil in operative position.

Fig. 7 is a perspective view illustrating 15 the three point support for a button as it is held during the process of forming a staple through the eye thereof.

Fig. 8 is a plan view of the forward end 20 of the staple former anvil constituting part of said three point support.

Figs. 9 and 10 are plan views of the staple forming and button setting mechanism the parts of said mechanism in the two views being in different positions.

25 Fig. 11 is a fragmentary side elevation of a portion of the means for operating the button stripping mechanism, the button removing mechanism, and the staple forming and setting mechanism.

30 Like reference characters refer to like parts throughout the several views of the drawings.

The machine illustrated is an improvement upon that covered by my prior Patent 35 No. 1,147,381, granted July 20, 1915, and, similarly, is carried by a suitable support 1 adjacent the forward end and above which an auxiliary support 2 is provided for carrying the major portion of the machine. A 40 bracket 3 is detachably connected to and extends to the rear from the support 2 and has spaced apart arms serving to support a horizontally positioned shaft 4. A bracket or casting 5 is loosely mounted upon the 45 shaft 4 by depending arms and includes a forwardly extended part 6 to which a block 7 may be detachably connected by means of screws or other suitable fastenings. The block 7 constitutes a supporting base for 50 a button transfer tube or raceway 8 which is permanently secured to the upper side of the block. This tube is formed of sheet metal fashioned at its under side into a substantially U-shaped guide slot 9 (see Figs. 5 and 7), the sides of which at their upper 55 ends are turned outwardly and then upwardly as indicated at 10 forming a widened shallow groove at the upper part of the guide slot. At the edges of this groove 10 the 60 sides are further extended laterally to provide button supporting surfaces 11 and then bent upwardly and inwardly toward each other, terminating at each side in ribs 12 bent inwardly toward the interior of the tube as 65 best shown in Fig. 4. Tube 8 in its upper

side has a slot 13 extending the full length thereof. The upwardly and inwardly turned sides of the tube terminate a distance back of the forward end of guide 9 while the button supporting surfaces 11 of the tube are extended and formed into flat fingers 14 separated by a notch substantially as wide as the shallow groove 10, this notch being preferably formed by cutting away the guide 9 and adjacent portions 10, as 75 shown in Fig. 7. This permits the eye of the button to be fully exposed when a wire is fed therethrough preparatory to forming a staple, even when the type of button which is provided with a neck or boss is used. This 80 construction of the forward end of the raceway is not claimed herein since it is shown and claimed in my pending application, Serial No. 128,617, filed Oct. 30, 1916.

The rear end of the button carrying tube 85 extends over the bracket 5 and over a ribbed roller 15 rotatively mounted therein. A block or like member 16 having a comparatively wide slot or way 17 cut therein which centrally is provided with the relatively 90 narrow slot 18 is secured at the back of bracket 5. The rear end of the button tube 8 (see Fig. 2) has portions removed directly in front of the way 17. The buttons 20 are mounted upon a long and comparatively 95 narrow strip of paper 19 which is entered into the way 17 and over roller 15 and under the parts 11 of the tube. The roller 15 is provided with a central groove 15^a in alignment with the slot 18 and adapted to pass 100 the shanks of the buttons. In practice the strip 19 and attached buttons are wound upon a reel 21 which may be rotatably supported by any suitable bracket 22 attached to and projecting to the rear from support 105 1. A ribbed roller 23, mounted upon a pivotally mounted support 24, is yieldingly pressed against roller 15 by the spring 25, and this roller 23 also has a groove 23^a as shown. A hand wheel 26 is connected to 110 the end of the shaft on which roller 15 is mounted and by turning the same the strip 19 may be manually fed between the rollers, so as to bring a series of buttons one by one up to the open upper end of 115 the raceway for insertion therein. At about the point where the strip is abruptly curved in its passage over the roller 15, the base of the button will be subtended by the lateral supporting surfaces 11 which, as shown 120 in Fig. 2, are separated by a notch as wide as the shallow groove of the raceway. If buttons of the type illustrated are being supplied, this notch will prevent interference between the end of the raceway and 125 the neck of the button and, regardless of the type of button, the advancing strip will carry the buttons forward to about the point shown in Fig. 5 where the paper mount is stripped away from the shank of 130

the button by the action of the rollers 15 and 23, leaving the button in the raceway. The buttons will be carried along the raceway by the action of gravity and the pressure of the succeeding buttons. It will be observed that the notches in the opposed ends of the raceway may be formed by tapering the tube vertically and preferably leaving the lateral button supporting surfaces 11. 5

10 The manual operation of this button stripping or removing means is intended to be used only in entering the mound 19 into the device and in stripping the first few buttons. The mechanism as a whole is designed to be power driven. To this end a bell crank lever having horizontal and vertical arms 27 and 28, respectively, is mounted on a pivot 29 on the auxiliary support 2. A link 30 connects the forward end of arm 27 with the forward end of a bar 31 pivotally mounted between its ends beneath the support 1 and connected at its rear end by a link 32 to a disk 34 eccentrically positioned on a shaft 33 which is driven in any suitable manner. The rotation of the shaft 33, it is apparent, causes the bell crank lever to be oscillated back and forth about its pivot. A link 35 (see Fig. 11) connects the upper end of arm 28 with a block 36 which is mounted for slidable movements. The link 35 is extended downwardly as shown at 37 and carries a laterally projecting pin 38 adapted to enter a slot in the widened forward section 39 of a link 40, as shown in Fig. 1, pin 38 being held in the forward end of said slot by a spring actuated dog 41. Disengagement of the pin 38 from the link 40 may be effected by releasing the dog 41 and allowing the pin to pass into the wider portion of the slot in the link 40. In case the parts connected to the link 40 become jammed or are otherwise rendered inoperative, the dog 41 will be pushed aside by reason of its sloping end and allow the pin 45 to pass along the slot in the link. The slope of the end of the dog 41 is sufficiently steep, however, to prevent this action except upon abnormal pressure. The link 40 curves upwardly and to the rear and is pivoted to a crank 42 loosely mounted upon the shaft 4. A dog 43 is pivotally mounted on the crank and engages with a ratchet wheel 44 fastened to one end of the shaft 4. The oscillation of the bell crank lever 50 moves the link 40 back and forth and on the forward movement of the link, the dog 43 rides over the teeth of the ratchet wheel while on the rearward movement of the link said dog, engaging with the teeth 55 of the ratchet wheel, gives a partial rotation to the shaft 4.

A combined cam and gear wheel 45 (see Fig. 3) is fastened on the shaft 4, the gear meshing with an idle gear 46 which in turn drives a pinion 47 secured to the shaft on which the roller 15 is mounted. It is apparent that the periodical partial rotation of shaft 4 gives the roller 15 also through this mechanism a periodical partial rotation, and the mechanism is so designed that with each 70 oscillation of the bell crank lever the rotation of rollers 15 and 23 is sufficient to move the mount 19 a distance substantially equal to that between successive buttons 20 whereby one button is removed and delivered to 75 the transfer tube with each oscillation of the bell crank lever.

The combined gear and cam wheel 45 carries a plurality of radially projecting cams 48. A pin or roller 49 projecting from the 80 lower end of the arm 50 of a bell crank lever pivotally mounted at 51 on the bracket 5 bears against the wheel 45 and rides against the cams and the intermediate surfaces of the wheel, a spring 52 serving to force said 85 member 49 against the wheel. The other arm 53 of the bell crank lever extends forwardly and upwardly and is bent over the button tube 8 and pivotally connected to a bar 54 which at its under side is formed with 90 a consecutive series of scallops 55 shaped to conform to the upper surface of the heads of shoe buttons. This bar is located directly above slot 13 of the button tube and is guided between guides 56 secured to and 95 projecting upwardly from the tube. A spring 57 carried by the arm 53 has a normal tendency to depress the forward end of bar 54. A pin 58 on the rear guide 56 extends through a relatively large opening in 100 the rear end of the bar 54 and stops said depression at a point where the bar is held substantially horizontal. In practice with each partial rotation of the shaft 4, the wheel 45 is moved a distance such that the 105 pin 49 passes from one projecting cam to the next succeeding cam, bar 54 during this movement being lowered and entering the slot 13 in the tube to engage with the buttons in the tube. It is apparent that with 110 the lowering of the bar there is also a slight forward movement imparted thereto which serves to slightly advance the buttons and right the same if any of them should become tilted so as to bind against any portion of 115 the tube. As the buttons pass down the tube they are stopped by fingers 59 pivotally mounted between upstanding brackets 60 adjacent the forward end of the tube and spring pressed so as to yieldingly hold the 120 buttons against passage from the tube.

The slidable block 36 heretofore noted has a pin 61 projecting laterally therefrom which engages with the link mechanism 62 for operating mechanism indicated as a 125 whole at 63 for lifting an ejecting finger 64 and causing it to engage with the foremost button in the tube directly behind the fingers 59. This mechanism is not specifically described as it forms no part of the present in- 130

vention but is fully described and shown in my patent to which reference has been made. With each oscillation of the bell crank lever arm 28, the finger 64 engages with and removes a button from the tube 8, carrying it to a position substantially like that shown in Fig. 1 with the button held against the forward end of a staple former 65 pivotally mounted between its ends as shown in Fig. 11.

The front end of staple former 65 is of special formation and is provided (see Figs. 9 and 10) with a comparatively wide transverse slot 66 back of which are located two upward projections 67 spaced from each other, while in front of the slot 66 a single upwardly projecting part 68 is formed having a width equal to the combined widths of the projections 67 and the space between them. The rear upper portion of the part 68 is formed with a curved depression below which and in alinement with the space between parts 67 is formed a vertical groove 70. The fingers 14 on the forward end of the button tube extend over the projections 67 and terminate directly above the slot 66, as shown in Figs. 1 and 3. This special formation is of particular value for the handling of the special form of button illustrated which has, on the under side of its head, a downwardly extending neck as shown at 71. This button forms the subject-matter of my Patent No. 1,206,755, granted Nov. 28, 1916. The eye 72 of the button which has been brought forward by the finger 64 enters the slots 66 and 70, being guided by the projections 67, after it has left the groove 9 while the neck 71 is received in the recess 69. The head of the button on the other hand is supported at the front by engaging against the upper side of part 68 while at the rear it is supported on both sides by the fingers 14, a three point support being formed in this manner which holds the button firmly against accidental displacement during the process of staple forming hereafter described. This support is also fully capable of handling the usual buttons, the heads of which are flat or slightly curved on the underside.

The block 36, which is operated in conjunction with the stripping mechanism, is connected with a slide 73 which, with the irregularly shaped member 74 pivotally connected thereto serves to operate the driver 75 and the wire cutting and staple forming member 76. The driver 75 is rigidly connected to the slide 73. With the forward motion of the slide 73, the member 76 cuts the wire 77 and fashions it into a staple, the member 75 modifying the upper part of the staple to adapt it for shoe button attachment as indicated in Fig. 9 and driving it into the work where it is clenched by the

anvil 84. The staple is formed around the rear portion of the part 68 and the member 65 is then oscillated to withdraw the part 68 and allow the staple to be driven. The wire is periodically fed forward through the eyes of buttons, as they are held in position upon their three point support by means of the lever 78 and its gripping dog 79, said lever having projecting legs 80 and 81 adapted to be engaged by a member 82 which is mounted on and movable with the slide 73. Retrogression of the wire is prevented by a holding bar 79^a. In addition this mechanism includes a spring controlled plunger 83 which is connected to the slide 73 and the member 82 and which is adapted to engage with and force bar 76 forward so as to hold the staple former 76 yieldingly against the work while the staple is being driven by the driver 75. The first part of said movement of the staple former 76 is positive by reason of the engagement of member 74 therewith while the concluding portion of the movement is yielding under the pressure of the spring pressed plunger 83. All of this mechanism is more fully shown and described in my patent to which reference has been made and is shown and described herein only to illustrate its operative combination and co-operation with the button stripping mechanism previously noted.

While the invention has been particularly described with reference to buttons and attaching staples, it will be understood that in some aspects it is of broader application and may utilize many other types of fasteners.

I claim:

1. In a machine for applying fasteners, means for independently and temporarily supporting each one of a plurality of fasteners arranged in a series, means for stripping said fasteners from the supporting means and presenting them one at a time for attachment to the work, and means for applying an attaching device to each fastener to secure it to the work.

2. In a machine for attaching buttons, a mount for individually and temporarily supporting a plurality of buttons arranged in a series for delivery to the machine, means for stripping a button from said mount and for presenting it in a predetermined position, and means for inserting a metallic fastening to attach the button to the work.

3. In a machine for applying fasteners, means for independently and temporarily supporting a plurality of fasteners arranged in a series, a fastener raceway, means including the raceway for stripping the fasteners from the temporary support for insertion in the raceway, and means for applying fasteners delivered by the raceway to the work.

4. In a machine for attaching buttons, a button raceway, means for individually and temporarily supporting a plurality of buttons arranged one after another for delivery to said raceway, means adjacent to one end of the raceway for stripping the buttons from the temporary support, means adjacent to the other end of the raceway for presenting a button in position for attachment to the work, and means for securing said button to the work. 65
5. In a machine for applying fasteners, means for individually and temporarily supporting a plurality of fasteners arranged in a series, a fastener raceway, means for stripping the fasteners from the temporary support for insertion in the raceway, means associated with the delivery end of the raceway for presenting a fastener in position for application to the work, and means for applying an attaching device to the fastener thus held. 70
- 10 6. In a machine for attaching fasteners, means for individually and temporarily supporting a plurality of fasteners arranged in a series, a fastener raceway, means for stripping the fasteners from the temporary support for delivery to the raceway, means associated with the delivery end of the raceway for presenting a fastener in position for application to the work, and a single driving means for said fastener stripping mechanism and said fastener presenting mechanism. 75
- 15 7. In a machine for attaching fasteners, a support in which a plurality of fasteners is arranged in a series, a fastener raceway, means acting on the support for stripping the fasteners therefrom for insertion in the raceway, means associated with the delivery end of the raceway for applying the fasteners to the work, and a single driving means for said fastener stripping means and said applying means. 80
- 20 8. In a machine for attaching buttons, means adapted to individually and temporarily support a plurality of buttons arranged in a series, a button raceway, a stripper mechanism for removing the buttons from their temporary support and introducing them into the raceway, means for intermittently removing a button from the raceway and positioning it for attachment to the work, means for attaching said button to the work, and a single driving means for said stripper mechanism, said positioning means and said attaching means. 85
- 25 9. In a machine for attaching buttons, means for individually and temporarily supporting a plurality of buttons arranged in a series, a button raceway, stripper mechanism for removing the buttons from the temporary support for delivery to the raceway, means for removing a button from the raceway and presenting it in a defined position, and means constructed and arranged to operate said stripper and said button removing and presenting means with a predetermined speed ratio whereby the average number of buttons in the raceway at one time may be accurately controlled. 90
- 30 10. In a machine for attaching buttons, means for individually and temporarily supporting a plurality of buttons arranged in a series, a button raceway, stripper mechanism for removing the buttons from the temporary support for delivery to the raceway, means associated with the delivery end of the raceway for removing a button therefrom and attaching it to the work, and means constructed and arranged to operate said stripper mechanism and the said removing and attaching mechanism with a predetermined speed ratio whereby the average number of buttons in the raceway may be accurately controlled. 95
- 35 11. In a machine for attaching buttons, means for individually and temporarily supporting a plurality of buttons arranged in a series, a button raceway, stripper mechanism for removing the buttons from the temporary support for delivery to the raceway, means for removing a button from the raceway and positioning it, staple forming mechanism associated with said positioning means, and means constructed and arranged to operate said stripper mechanism and said staple forming mechanism with a predetermined speed ratio. 100
- 40 12. In a machine of the character described, means for holding a shoe button, means for forming a staple through the eye of the button thus held, a transfer tube for carrying buttons to said holding means, a stripping mechanism at one end of the tube for receiving a mount having buttons mounted in succession thereon and for stripping said buttons from the mount and delivering them to the tube, and mechanism for operating the stripping and staple forming means in conjunction with each other whereby for each button delivered from the tube another button is delivered to the tube by said stripping mechanism. 105
- 45 13. In a machine of the character described, a button transfer tube, a stripping mechanism at one end of the tube adapted to receive a mount carrying shoe buttons mounted in succession thereon and strip said buttons from the mount delivering them to the tube, a support for buttons in front of the opposite end of the tube, means for removing buttons from the tube and placing them on said support, means for forming a wire staple through the eye of each button on the holder, and means for periodically operating said stripping, staple forming and removing means in conjunction with each 110
- 50 14. In a machine of the character described, a button transfer tube, a stripping mechanism at one end of the tube adapted to receive a mount carrying shoe buttons mounted in succession thereon and strip said buttons from the mount delivering them to the tube, a support for buttons in front of the opposite end of the tube, means for removing buttons from the tube and placing them on said support, means for forming a wire staple through the eye of each button on the holder, and means for periodically operating said stripping, staple forming and removing means in conjunction with each 115
- 55 15. In a machine of the character described, a button transfer tube, a stripping mechanism at one end of the tube adapted to receive a mount carrying shoe buttons mounted in succession thereon and strip said buttons from the mount delivering them to the tube, a support for buttons in front of the opposite end of the tube, means for removing buttons from the tube and placing them on said support, means for forming a wire staple through the eye of each button on the holder, and means for periodically operating said stripping, staple forming and removing means in conjunction with each 120
- 60 16. In a machine of the character described, a button transfer tube, a stripping mechanism at one end of the tube adapted to receive a mount carrying shoe buttons mounted in succession thereon and strip said buttons from the mount delivering them to the tube, a support for buttons in front of the opposite end of the tube, means for removing buttons from the tube and placing them on said support, means for forming a wire staple through the eye of each button on the holder, and means for periodically operating said stripping, staple forming and removing means in conjunction with each 125

other whereby each button removed from one end of the tube is followed by the delivery of another button to the tube at the other end thereof by said stripping mechanism.

14. In a machine for attaching buttons, a readily removable, detachable button raceway provided at its delivery end with spaced apart button supporting surfaces, a movable former anvil adapted to be positioned adjacent to said supporting surfaces and arranged to form a three-point support therewith for a button, and means for clamping a button in position so that it is supported upon the spaced apart extensions of the button raceway and upon said former anvil.

15. In a machine for attaching buttons, a downwardly inclined button transfer tube provided with spaced apart forwardly projecting, flat fingers adapted to underlie the base of a button, and a pivotally mounted former anvil having a projecting end adapted to be moved into and out of position adjacent to said flat fingers and arranged to constitute with said fingers a three-point support for a button delivered from the body of the raceway.

16. In a machine for attaching buttons, a downwardly inclined button transfer tube provided with forwardly extending, spaced apart fingers adapted to underlie the base of a button, a former anvil provided with a projecting end adapted to be associated with said projecting fingers to form thereby a three-point support for a button delivered from the body of the raceway, said former being movable into and out of position adjacent to the fingers and a staple forming and driving mechanism associated with said former anvil and said raceway.

17. In a machine for attaching buttons, a button transfer tube provided at its forward end with a pair of spaced apart fingers, a member provided with a projecting end located in front of and spaced from the forward ends of the fingers, said projecting end and said fingers serving as a three-point support for a button delivered from the tube, and means for taking a shoe button from the tube and holding it on said three-point support.

18. In a machine of the character described, a button transfer tube provided at its forward end with a pair of spaced apart fingers, means for delivering shoe buttons into the tube, a member including two spaced apart upward projections located below the forward ends of said fingers and a third upwardly projecting part located in front of and spaced from the forward ends of the fingers, said forward ends of the fingers and said last mentioned upwardly projecting part serving as a three point support for shoe buttons taken from the tube, and means

for taking a shoe button from the tube and holding it on said three point support, substantially as described.

19. In a machine for attaching buttons, a button transfer tube or raceway provided at its forward end with a pair of forwardly extended, spaced apart fingers, a member provided with two spaced apart, upward projections located beneath the forward ends of the said fingers and a third projecting part in front of and spaced from said projections, means for taking a button from the tube and holding it on the said fingers and said third projecting member as a three-point support therefor, and means for threading a wire staple through the eye of a button thus held.

20. In a machine for attaching buttons, a button raceway provided with forwardly extended, spaced apart supporting fingers, a former anvil provided with a projecting end adapted to be positioned in front of and adjacent to said supporting ends, thereby to constitute a three-point support for a button, means for taking a button from the raceway and holding it on said support, and means for forming a staple through the eye of a button thus held.

21. In a machine of the character described, a button transfer tube provided at its forward end with a pair of forwardly extended spaced apart flat fingers, means for delivering shoe buttons into the tube, yielding means normally stopping the passage of buttons from the tube, a member located below the tube and including two spaced apart upward projections located below the forward ends of said fingers and a third upwardly projecting part in front of and spaced from said projections, means for periodically taking a button from the tube and holding it on the forward ends of said fingers and said third upwardly projecting part as a three point support therefor, and means for forming a wire staple through the eye of each button thus held, substantially as described.

22. In a machine of the character described, a downwardly inclined button transfer tube, spaced apart forwardly projecting flat fingers at the forward end of the tube, and a member pivotally mounted below the tube including three upwardly projecting parts, one in front of the forward ends of said fingers and the other two spaced apart from each other and the first mentioned part and located below the forward ends of said fingers, substantially as described.

23. In a machine for attaching buttons, a button raceway provided with spaced apart, forwardly extended supporting fingers, and a member having an upwardly projecting end adapted to be positioned in front of and adjacent to said supporting fingers so that

its upper end in connection with said fingers constitutes a three-point support for a button taken from said raceway, the upper end of said member being provided with a shallow curved recess facing toward said spaced apart fingers and dimensioned to cooperate with the space between the fingers to receive a boss or neck upon the base of a button supported by said member and said 10 fingers.

24. In a machine for attaching buttons, a staple former anvil adapted to be associated with a button delivering and a wire feeding means, said former anvil being provided with an upwardly projecting end having a transverse wire threading recess, a staple forming surface at one side of said recess and a button shank guiding means at the other side of said recess, the upper end 15 of said former in front of said wire threading recess being constructed and arranged to constitute part of a button support and being provided with a shallow recess facing toward the wire threading recess and adapted 20 to receive the neck or boss upon the base of a button which is supported, at least in part, upon said former during the staple forming operation.

25. In a machine of the character described, a downwardly inclined button transfer tube, spaced apart forwardly projecting flat fingers at the forward end of the tube, and a member mounted below the tube including three upwardly projecting parts, 30 two of which are spaced apart and located below the free ends of said fingers, the third part being located in front of and spaced from the free ends of said fingers and provided with a curved recess in its rear upper portion and with a central vertical slot 35 in the rear face thereof, substantially as described.

26. In a machine for attaching buttons, a button raceway provided with a longitudinal groove adapted to receive the eyes of the buttons, said groove being widened at its upper portion to receive a projection upon the base of the buttons, and a slot at either end of said raceway substantially of 40 the width of the projections upon the base of the buttons, a stripper mechanism associated with one end of said raceway adapted to remove buttons from a temporary support and insert them in proper position in 45 the raceway, and a threaded mechanism associated with the other end of the raceway and adapted to cause the threading of the shank of a button with the staple wire as the button is supported, at least in part, on 50 the slotted end of the raceway.

27. In a machine for attaching buttons, a button raceway provided with a longitudinal groove adapted to receive the eyes of the buttons, said groove being widened at

its upper portion to receive a projection 65 upon the base of the buttons, and a slot at either end of said raceway substantially of the width of the projections upon the base of the buttons, a stripper mechanism associated with one end of said raceway adapted 70 to remove buttons from a temporary support and insert them in proper position in the raceway, and a staple former anvil having a projecting end adapted to be positioned substantially in said slotted end of 75 the raceway to assist in the formation of the staple through the eye of a button which is supported at least in part upon the end of the raceway.

28. A button raceway having a longitudinal slot extending from the exit end for some distance toward the opposite end of substantially greater width than the width of the eye of the button and of sufficient width so that a boss on the under side of 80 the button may project down through said slot while the button head rests upon the upper side edges of the raceway and permits the eye which projects downward from said boss to be entirely below the base of 85 the raceway, and means for clamping the button temporarily within said slot in the raceway in order to be threaded with a wire 90 for a fastener.

29. In a machine for attaching buttons, 95 a button raceway having a longitudinal slot at the exit end of a width substantially greater than the width of the shank receiving groove of the raceway and less than the width of the base of the button supported in the raceway so that a boss upon 100 the under side of the button may project down through said slot while the button head rests upon the side edges of the raceway, and means for threading the eye of 105 a button thus positioned with a staple wire.

30. In a machine for attaching buttons, a button raceway having a longitudinal slot at the exit end of a width substantially greater than the width of the shank receiving groove of the raceway and less than the width of the base of the button supported in the raceway so that a boss upon 110 the under side of the button may project down through said slot while the button head rests upon the side edges of the raceway, means for threading the eye of a button thus positioned with a staple wire, and means for forming said wire into a staple 115 within the eye of the button.

31. In a machine for attaching buttons, a button raceway having a longitudinal slot at the exit end of a width substantially greater than the width of the shank receiving groove of the raceway and less than 120 the width of the base of the button supported in the raceway so that a boss upon the under side of the button may project

down through said slot while the button head rests upon the side edges of the raceway, means for threading the eye of a button thus positioned with a staple wire, 5 means for forming said wire into the staple within the eye of the button, and means for driving said staple to attach the button to the work.

32. In a machine for attaching buttons, 10 a button raceway having a longitudinal slot at the exit end of a width substantially greater than the width of the shank receiving groove of the raceway and less than the width of the base of the button supported in the raceway so that a boss upon the under side of the button may project down through said slot while the button

head rests upon the side edges of the raceway, and a staple former anvil adapted to be positioned adjacent to the slotted end 20 of the raceway and having a shank guiding means underlying the slot in the end of the raceway.

33. In a machine for applying fasteners, means for independently and temporarily 25 supporting a plurality of fasteners arranged in a series, means for removing the fasteners from the temporary support, and means for applying an attaching device to the fastener which has been removed from 30 the temporary support to secure said fastener to the work.

In testimony whereof I affix my signature.
WILLIAM E. ELLIOTT.
